UNITED STATES PATENT OFFICE.

LUCIAN W. BUGBEE, OF INDIANAPOLIS, INDIANA, ASSIGNOR TO ONEPIECE BIFOCAL LENS COMPANY, OF INDIANAPOLIS, INDIANA, A CORPORATION.

MEANS FOR POLISHING MULTIFOCAL LENSES.

1,397,399.

Specification of Letters Patent. Patented Nov. 15, 1921.

Application filed March 13, 1920. Serial No. 365,400.

To all whom it may concern:

Be it known that I, LUCIAN W. BUGBEE, a citizen of the United States, and a resident of Indianapolis, county of Marion, and State 5 of Indiana, have invented a certain new and useful Means for Polishing Multifocal Lenses; and I do hereby declare that the following is a full, clear, and exact description thereof, reference being had to the accompanying drawings, in which like numerals refer to like parts.

The object of this invention is the improvement in the polishing of the surfaces of bifocal lenses and it relates particularly 15 to means for simultaneously polishing the distance and reading surfaces of bifocal lenses by independent polishing buttons or tools for said surfaces so as to polish said surfaces uniformly and perfectly.

20 The chief feature of the invention consists in providing holding means for said plurality of polishing buttons or tools which will keep the same operating on their respective surfaces and accurately positioned 25 so as to polish the surfaces throughout their areas evenly and up to the line of division between the surfaces and exert a pressure on the polishing buttons approximately in proportion to their sizes so as to cause the 30 polishing thereof.

Heretofore in the practice in the manufacture of such lenses the two surfaces have been successively polished by independent means, at least where accurate polishing and 35 optically perfect bifocal lenses were desired. This invention is to do such work simultaneously and yet perfectly and attain as nearly as possible the ideal of equivalent treatment of both surfaces.

40 The full nature of the invention will be understood from the accompanying drawings and the following description and claims:

In the drawings, Figure 1 is a side elevation 45 of a portion of a lens polishing machine including this invention. Fig. 2 is a plan view of what is shown in Fig. 1. Fig. 3 is a vertical sectional view through parts of the machine showing the lens blank and 50 holder in central vertical section, the remaining parts being in front elevation and partially broken away. Fig. 4 is a plan view of the lens blank shown in Fig. 3 and the polishing buttons thereon. Fig. 5 is a plan

view of the blank after it has been polished, 55 the lines on which it is cut to form the final completed lenses being indicated by dotted lines. Fig. 6 is a section on the line 6—6 of Fig. 3. Fig. 7 is a section on the line 7—7 of Fig. 3.

There are shown in Figs. 1 and 2 parts of a machine in connection with which this invention has been and can be used, although most parts of the machine are old. There is shown a table 10 with a vertical shaft 11 60 mounted in the bearings 12, said shaft carrying a removable lens holder 13 of common type on which a target lens blank 14 is secured for treatment. The shaft 11 is driven by means of a pulley 15 and belt 16. On 65 said table there is a base plate 110 carrying stationary bearing posts 17 carrying bearings 18 in which bearing screws 19 are horizontally mounted, as shown in Fig. 2, in connection with which the arm or frame 20 70 is pivoted at its rear end and its front end is acted upon by gravity for exerting pressure on the polishing means or buttons. The gravity can be increased by adding additional weights, not shown, as is often done 75 in the practice.

In Fig. 3 there is shown a front elevation of the front end of the arm 20 which has a segmental-shaped plate 24 rigid therewith. The clamping plate 25 is associated with the 80 plate 24 for clamping a rod 26 in proper position. Bolts 27 secure the plate 25 in position and one of these bolts extends through a slot 28 in the plate 24 so that the angular position of the clamping plate 25 85 may be adjusted in order to hold the rod 26 in proper inclination.

The bifocal lens blank 14 as shown in Fig. 3 is secured on the lens holder 13 and has a central area 30, which is the reading surface 90 of the lens blank, and the surrounding annular area 31, which is the distance surface of the lens blank. These two surfaces appear in Fig. 4, and are there shown separated by a division line 32, although in the 100 actual lens said division line is practically invisible. For polishing the central or reading surface 30 a small button 35 is used and for polishing the surrounding surface 31 a larger button 36 is used. The small 105 button has a diameter equal to one-half of the diameter of the reading surface 30 and the large polishing button has a diameter

equal to the width of the distance surface 31 between the edge of the blank and the reading surface. Said blank is what is known in the trade as a target lens bifocal blank. Said two surfaces have been generated to give them the proper relative curvatures, prior to the polishing operation by the means herein set forth.

The lens holder and lens are rotated and 10 the polishing buttons 35 and 36 are held in place by pins 37 and 38, respectively, arranged so as to permit the polishing buttons to revolve on the lens blank as they may be caused to revolve by the rotation of 15 the blank. This usually gives sufficient revolution of the buttons to cause the desired cross rubbing, as the buttons will rotate substantially at the speed of the lens blank at its line of contact with the polishing button 20 farthest from the center of the lens blank.

The pins 37 and 38 are secured in a bar 40 pivoted by a pin 41 to the lower end of the rod 26. This enables the bar 40 to rock and permit the polishing buttons to fully 25 engage and accommodate themselves to the surfaces of the blank during the polishing operation, and the weight of the arm 20, rod 26, bar 40 and pins 37 and 38 will be constantly exerted on the polishing buttons 30 in order to cause the friction desired for the polishing action.

In order to cause an equivalent polishing action by the two buttons, the bar 40 is provided with a number of holes 42 so that it 35 can be properly pivoted to effect said result. To this end the bearing pin 41 should be located at a point near the pin 38 of the larger button, for since the large button has two or three times the polishing surface of 40 the small button, there should come to it through the pin 38 proportionately more pressure. Therefore, the distances between the pivot 41 and the pins 37 and 38 should be substantially in reverse ratio to the diameters of the buttons.

Since the relative distances of travel on the lens blank of the outer and inner edges of the large button 36 are not relatively great, the outer portion of said button does 50 not always rotate with the blank and it is desirable for that button to always rotate to effect cross polishing. Therefore, the two buttons are connected by a belt 50 in grooves 51 so that the small button will always cause 55 the large button to rotate. Since the glass blank under the outer edge of the small button travels infinitely faster than the portion under the inner edge of the small button, which is at the center of the lens blank, 60 the lens blank always causes the outer portion of the inner button to rotate in the same direction as the blank.

In order to accommodate the rocking pin frame to buttons of varying diameters or to 65 lens blanks of varying dimensions, the pins

37 and 38 are adjustably mounted in the bar 40 so as to be adjusted toward or away from each other. This is illustrated in Fig. 6, which shows a longitudinal slot 60 in the bar 40 through which the shank of the pin extends and it is screw threaded and a nut 61 on the upper end clamps the pin in adjusted position.

The invention claimed is:

1. Means for simultaneously polishing a 75 plurality of concentric surfaces of lens blanks including a polishing button for each surface, a pin frame having a pin for loosely engaging each button, and vertically movable means to which said pin frame is pivoted between the pins so the pin frame can 80 rock thereon vertically.

2. The combination with a lens holder for holding a lens blank having a plurality of concentric surfaces to be polished, and means 85 for rotating the same, of a polishing button for each surface thereof, a pin frame having a pin for loosely engaging each button, and vertically movable means to which said pin frame is pivoted between the pins so the 90 pin frame can rock thereon vertically.

3. The combination with a rotary lens holder adapted to hold a lens blank having a central portion and a surrounding annular portion, of a polishing button for the 95 surrounding annular portion with a diameter substantially the same as the width of said surrounding portion, a polishing button of a smaller size for the inner portion having a diameter substantially one-half of said portion, a pin frame with a pin engaging each of said buttons and arranged so as to hold the button for the inner portion between the center and circumference of said portion and to hold the button for polishing the outer portion between the inner and outer peripheries of said portion, and vertically movable means to which said pin frame is pivoted between the pins so that it can rock vertically.

4. Means for polishing simultaneously the surfaces of a lens blank having a central circular surface and a surrounding annular surface, including a small polishing button for the central surface and a larger polishing button for the surrounding surface, a pin frame having substantially parallel pins secured therein for engaging and holding the buttons on the respective surfaces of the lens, and vertically movable means to which said pin frame is pivoted between the pins at a point nearer the pin for the large button than the pin for the small button in order to equalize more nearly the polishing action of the buttons.

5. Means for polishing simultaneously the surfaces of a lens blank having a central circular surface and a surrounding annular surface, including a polishing button for the central surface and another polishing 130

button for the surrounding surface, a pin for engaging and holding each button in place, a bar to which said pins are secured which has a series of pivot holes in it, and 5 vertically movable means pivotally connected with said bar in one of said pivot holes.

6. Means for polishing simultaneously the surfaces of a lens blank having a central circular surface and a surrounding annular 10 surface, including a polishing button for the central surface and another polishing button for the surrounding surface, a pin for engaging and holding each button in place, a bar in which said pins are mounted, means 15 for adjustably mounting the pins in said bar so that the pins can be adjusted toward or away from each other, and vertically movable means to which said bar is pivoted between said pins.

20. Means for simultaneously polishing a plurality of concentric surfaces of lenses including a polishing button for each surface adapted to have free rotation, a single mechanism for holding them in position on 25 said surfaces but permitting independent vertical movement of the buttons, and a belt connecting said buttons so that one button

will influence the rotation of the other button.

8. The combination with a lens holder 30 adapted to hold a lens blank having a round central surface and a surface surrounding said central surface, and means for rotating said lens holder, of a button for polishing each of said surfaces, means for holding said buttons in place so they can rotate and polish said lens blank surfaces simultaneously, and a belt connecting said buttons so one will influence the rotation of the other.

9. Means for polishing simultaneously the 40 surfaces of a lens blank having a central circular surface and a surrounding annular surface, including a small polishing button for the central surface and a larger button for the surrounding surface, a pin frame 45 having a pin for engaging and holding each of said polishing buttons, vertically movable means to which said pin frame is pivoted between said pins, and a belt connecting said buttons for enabling the smaller button 50 to control the rotation of the large button.

In witness whereof, I have hereunto affixed my signature.

LUCIAN W. BUGBEE.
